UNITED STATES PATENT OFFICE

HARTLY L. BATEMAN, OF FREDONIA, KANSAS

STREET MARKER

Application filed June 27, 1930. Serial No. 464,343.

The invention aims to provide an exceptionally simple and inexpensive, yet a desirable and attractive street marker which may be easily positioned and anchored upon a street-bordering curb or at or near the line usually occupied by a curb.

With the foregoing in view, the invention resides in the novel subject matter herein-after described and claimed, description being accomplished by reference to the accompanying drawings.

Fig. 1 is a perspective view of the marker showing the curb in dotted lines.

Fig. 2 is a transverse sectional view through the marker, the curb, a portion of the material retained by said curb, and a portion of the street.

Fig. 3 is a transverse sectional view showing another manner of using the marker.

The preferred details of construction are illustrated in the accompanying drawings, and while these details will be specifically explained, it is to be understood that within the scope of the invention as claimed, minor variations may be made.

The numeral 5 denotes a horizontally elongated block formed from concrete, metal or other desired material, said block having a flat lower side 6 adapted to rest upon a curb 7. At one longitudinal edge, the block 5 is provided with an integral, downwardly projecting, longitudinal flange 8, constituting an anchor. One vertical longitudinal side 9 of this flange is flat and is adapted to abut the inner side of the curb 7. The other vertical longitudinal side 10 of the flange 8 is also flat, and this side is provided with an integral, laterally projecting, longitudinal anchoring rib 11, said rib being disposed at the lower edge of said flange.

Above the flat lower side 6, the obverse and reverse sides 12 and 13 of the block 5, preferably converge upwardly, and one or both of these sides, may carry a sign 14 giving the name of a street, the letters or numbers embodied in the sign being preferably raised and formed integrally with the block. The upper longitudinal edge 15 of the block is preferably flat and horizontally disposed.

In mounting the improved marker upon

a curb, it is simply necessary to dig out some of the earth E or other material retained by the curb, for reception of the anchoring flange 8. The device is then so positioned that its surfaces 6 and 9 snugly rest against the curb 7, and some of the removed earth or other material E is then solidly replaced, embedding the flange 8 and insuring effective anchorage of the device. When so anchored, the street name is very conspicuously displayed, the inclination of the outer side 12 of the block 5 serving not only to dispose said name in a plane at substantially right angles to the line of vision when glancing downwardly, but also giving sufficient clearance to prevent wheel hubs from striking the marker when parking or traveling near the curb.

While the invention is intended primarily for mounting on a curb as above described, it may merely rest upon the ground with the flange 8 embedded in the latter, as illustrated in Fig. 3.

I claim:

1. A marker comprising a horizontally elongated sign-bearing block having a flat lower side adapted to rest upon a curb, one longitudinal edge of said block being provided with an integral downwardly projecting longitudinal flange adapted to be embedded in the material retained by the curb, said flange being flat at one vertical longitudinal side to abut the curb and being provided on its other vertical longitudinal side with an integral laterally projecting anchoring rib, said rib extending longitudinally of said flange at the lower edge of the latter.

2. A structure as specified in claim 1; the obverse and reverse longitudinal sides of said block being flat and disposed in upwardly converging relation above said flat lower side.

In testimony whereof I affix my signature.

HARTLY L. BATEMAN.
